UNITED STATES PATENT OFFICE.

WOLFGANG HERMANN, OF CHICAGO, ILLINOIS, ASSIGNOR TO METAL SPECIALTIES MANUFACTURING COMPANY, OF CHICAGO, ILLINOIS, A CORPORATION OF ILLINOIS.

ANIMATED-PICTURE DEVICE AND METHOD OF MANUFACTURE.

Application filed February 5, 1925. Serial No. 7,018.

This invention relates particularly to mechanism adapted to produce the illusion of motion, or animation, in pictorial scenes. For example, such a device may be employed 5 to produce the illusion of a water-fall, in motion, by projecting lights and shadows in a suitable manner through a transparency bearing, or having associated therewith, the picture, or the painting, of the natural 10 scenery which includes the water-fall. In effect, lights and shadows are cast upon, or projected through, a transparent picture, the light first passing through a suitable screen, or screens, at least one of which is 15 in motion. The lights, passing in waves through the picture-transparency, produce the illusion of motion in the water-fall in the particular adaptation mentioned.

The principle described is capable of application to an exceedingly wide range of 20 subjects, and effects of exceedingly great artistic merit can be simply and cheaply obtained. The present invention relates especially to means for rendering practicable 25 the use of very simple and inexpensive means for projecting the lights and shadows which are desired to produce an illusion of the character described.

In the preferred embodiment of the invention, use is made of a rotary screen which 30 is caused to revolve by ascending air-currents caused by lamps, which serve both as a source of power for the screen and as a means of casting the moving lights and shadows. Because of the very low amount 35 of power available from such a source, efforts hitherto made to produce a practicable device operating on this principle which could be depended upon to continue in operative condition for any considerable 40 period of time have not met with full success. The present invention overcomes the difficulties which have been encountered, and provides a thoroughly practicable mechanism.

45 The primary object is to provide improved mechanism of the character referred to, and an improved method of manufacturing the same.

The invention is illustrated in its preferred embodiment in the accompanying drawings, in which—

Fig. 1 represents a vertical sectional view

of shadow and light projecting mechanism embodying the invention, the lamp-supporting stand being shown in elevation; Fig. 2, a plan view of an air-driven fan upon which the rotary screen is mounted; Fig. 3, a horizontal sectional view taken as indicated at line 3 of Fig. 1; Fig. 4, an edge elevational view of the propeller-fan employed, with the blades set at an angle approximating that required for maximum speed; Fig. 5, a similar view showing the blades set at an angle corresponding approximately with the slowest speed desired; Fig. 6, a sectional view of a cabinet equipped with the improved shadow and light projecting mechanism; Fig. 7, a broken horizontal section taken as indicated at line 7 of Fig. 6; Fig. 8, a broken view of a screen interposed between the revolving screen and the picture-transparency; Fig. 9, a broken vertical sectional view showing a modification of the device for suspending the propeller-fan and rotary screen carried thereby; and Fig. 10, a broken plan view of a modification of the fan.

In the embodiment illustrated. A represents a cabinet whose front may be left open, except that a suitable molding A', which is in the nature of a picture frame, may be provided; A² designates a picture-transparency mounted in the frame A'; A³ designates a lid for the cabinet; B designates the improved shadow and light projecting mechanism, which comprises a stand B', a propeller-fan B² having a balanced suspension on the upper end of the stand, and a rotary screen B³ suspended from, and actuated by said propeller-fan; and C designates a stationary screen interposed between the rotary screen and the picture-transparency A².

The stand B' preferably comprises three vertical steel rods 1, two of which are diametrically opposite each other, and the third of which is in the rear; a bottom plate 2, a top plate 3, an upper intermediate plate 4, and a lower intermediate plate 5 secured to said rods; and a central stem 6 carried by the upper disk 3 and comprising a socket piece 6^a rigidly attached to the disk, and a removable needle, or stem point, 6^b mounted in said socket.

The preferred manner of assembling the stand is to provide the disks, or plates, men-

tioned with perforations 7 through or into which the rods extend. The perforations in the disks 4 and 5 may be drilled or punched so as to be the same distance from the centers 5 of the disks. It is preferred to provide the perforations in the disks 3 and 2 at distances from the centers which are different from those employed at the disks 4 and 5. Thus, it is preferred to make the perforations 10 of the disk 3 on a smaller radius, and perforations 7 of the disk 2 on a larger radius than are the perforations of the disks 4 and 5. The rods 1 which are employed are stiff 15 resilient rods. These are sprung when the rods are entered in the perforations and thus put under flexion. The result is to cause the rods to bind strongly in the perforations in the disks and produce an exceedingly rigid stand which, nevertheless, is of very light 20 construction. To make the connections still more secure, solder may be applied at the joints between the rods and the disks, as indicated at 7^a.

The socket-member 6^a which is secured to 25 the upper end of the stand may be of any suitable metal, such as brass. The lower end of this member may be provided with a reduced threaded portion 6^c which passes through a perforation in the center of the 30 top disk and is secured by means of a nut 8. The member 6^b preferably is of organic composition and of fibrous character. It is preferred to employ a needle consisting of, or comprising, bamboo fibre, such as is commonly used for phonograph needle purposes. When desired, the needle may be lifted out 35 of the socket and a fresh needle may be inserted.

The propeller-fan B² preferably consists 40 of an aluminum disk which is suitably incised and stamped to provide blades 9. The central portion of the aluminum disk is provided with a perforation in which is fitted an inverted cup 10, which preferably is of 45 glass. In the illustration given, this cup is provided at its open end with an external flange 10^a. The cup is inserted through the central perforation in the fan and is removably held in position by means of a spring 50 ring 10^b.

The preferred method of forming the fan 55 is to provide the aluminum disk with an annular series of small perforations 11 which encircle the cup-receiving perforation at a suitable distance, incise the metal along radial lines 11^b which extend from the small 60 perforations to the periphery, and bend the sectors so as to provide the blades 9 which are disposed at a suitable angle with reference to the horizontal plane of the fan. An 65 inclination of about thirty degrees from the horizontal gives the fan its greatest efficiency. Any greater inclination beyond that which gives the maximum efficiency lowers 70 the efficiency, and thus makes the speed of

the fan slower. It is preferred to employ dies which will make the radial incisions and bend the sectors to the steepest angle which will be employed in practice, that is, the angle corresponding with the slowest speed. 70 To obtain higher speeds, the propeller-fan may be flattened to the extent desired between two flat plates. This may be done by setting the plates in a press and adjusting the press so that it will give a limited stroke sufficient to give the desired set to the blades. Propeller-fans, having different inclinations of blades, may be used interchangeably in connection with the rotary screen B³; and, 75 assuming the heating means employed in the stand, such as electric lamps, to remain the same, different rates of speed of the rotary screen may be obtained by using different fans whose blades are set at different angles. 80

The cylindrical screen B³ may be composed of any suitable transparent material which is light in weight. Celluloid, or a composition of that character, is well adapted to the purpose. The celluloid cylinder may be provided with opaque marks, or 85 lines, arranged in any desired way. In the illustration given, the exterior surface of the celluloid is provided with heavy opaque spiral lines 12, produced by applying a thick ink, pigment, or paint, in accordance with a selected design. The spiral lines may be varied, or broken, as indicated at 12^a, in such manner as to produce in the picture of the water-fall, for example, the effect of ripples, 90 or eddies, at or near the bottom of the waterfall. The casting of alternate lights and shadows through the rotary screen has the effect of producing the illusion of motion in the outline of a water-fall, for example, 95 which is traced in the opaque screen C. In 100 Fig. 6, the thickness of the lines may be as indicated at the upper portion.

The screen C may comprise a plate of 105 glass 13 having an opaque coating 13^a in which is traced lines 13^b representing the 110 outline of a water-fall. These lines may be provided by scratching off the opaque coating, so that light will be transmitted through the glass at the lines. The outline of the 115 water-fall on the screen C will correspond, in a general way, with that portion of the 120 painting at the picture-transparency A² which represents the water-fall, thus, there 125 will be produced the illusion of falling water, eddy effects, etc., as may be desired. The painting may represent, for example, 130 a stream set in mountain scenery and containing boulders, and exceedingly realistic effects may be obtained. The picture, or painting, may be provided and set in the frame A', in any suitable manner. In the example given, the painting is provided on a film, or thin sheet of paper, if desired, 14, 135 which is interposed between glass plates 14^a. The transparency is mounted in suitable 140

lateral guide-slots 15 with which the picture-frame A' is provided. The upper ends of these channels may be left open, so that when the lid A³ is lifted, a picture may be removed or inserted, as desired.

The source of heat preferably comprises electric lamps 16 and 17 mounted in insulating sockets 16^a and 17^a, respectively, which are applied at central perforations with 10 which the intermediate disks 4 and 5 are provided. The sockets may be constructed in any desired manner to enable them to be applied to the disks. Electric conductors 18 are suitably connected with the sockets. 15 Any suitable means, not shown, for controlling the circuits may be provided. The disks 2, 3, 4 and 5 are preferably provided with perforations 19 which encircle the central portions and provide air passages. The 20 purpose is to permit the ascending air currents to strike the propeller-fan in an advantageous manner.

The lower disk 2 which constitutes the base of the stand B' is secured to the floor 25 of the cabinet in a suitable manner, as by means of screws 20; and the floor of the cabinet preferably is provided with air inlets 21 which register with the passages through the disk 2. Air registers may be employed, 30 if desired; and, if desired, the lid A³ may be provided with perforations 22 to permit a free circulation of air.

In Fig. 4, an edge elevational view of the propeller-fan B² is shown. This fan has 35 its blades set at an angle which approximates, but probably is somewhat greater, than the angle of greatest efficiency.

In Fig. 5, B⁴ represents a similar fan with the blades set at an angle of low efficiency, corresponding with slow speed. The fan shown in Fig. 5 may be assumed, in the preferred method of manufacture, to represent one stage in the manufacture of the fan 40 shown in Fig. 4.

The method of mounting the propeller-fan on the stand B' may be varied. In the modification shown in Fig. 9, B⁵ designates the central portion of a propeller-fan having a central perforation fitted with a removable needle 6^c, whose point is presented 45 downwardly; and 10^c designates a cup, or bearing, mounted in a supporting spider 23 which is secured to the top disk 3 of the stand. It will be understood that the fan 50 B⁵ has suspended from it the screen B³.

One manner of supporting the screen B³ on the propeller-fan is to fit within the upper end of the screen a ring 24 which thus provides at its lower edge an internal shoulder, or stop, which rests upon the fan-blades at their outer ends. The fan may be inserted through the cylinder from below with a friction fit, so that the screen B³ will 60 rotate with the fan.

It is of the utmost importance in a device

of this character, where the propeller-fan and screen carried thereby are actuated by means of heated air currents, that the suspension device should be of such character as to produce the minimum amount of friction, avoid abrasion, and prevent the accumulation of any substances at the point of contact which might interfere with the operation. The power available is very small, indeed. It has been found that those materials which ordinarily would be employed for bearing purposes will not serve the purpose best in the present case. For example, brass to steel, steel to glass, etc. will not serve the purpose to good advantage. In 70 general, the use of metals either alike or unlike, is not desirable. It might be thought that the use of one hard metal and one softer metal would answer the purpose, but such has not proven to be the case. In 75 general, the use of metals results in abrasion and collection of minute particles at the contact surfaces, which will, in time, stop the operation. The use of a steel point in a 80 glass-cup bearing has not proven very satisfactory.

On the other hand, there may be substituted for a glass-cup bearing any bearing having similar characteristics; also, there may be substituted for the needle of bamboo fibre any needle having similar characteristics. In general, one of the bearing members may be formed of suitable mineral material which can be properly molded and melted, or vitrified, so as to give a smooth, or glazed surface; and the other member may be of organic material, or composition, preferably of fibrous material. Hard fibre, for example, may be employed in lieu of the bamboo wood. 105 However, the substances thus far found most suitable are glass against bamboo fibre, and the bamboo shaft or needle has the grain running longitudinally, so that the needle will not wear readily; and, evidently, such wear as does occur does not result in either abrading the glass or interposing any gritty, or sticky, material at the point of contact.

In the construction described, the screen and propeller-fan are suspended on the needle in such manner that there is no possibility of wedging, and the screen and fan can balance themselves, at all times, properly on the needle point. It has been found that a comparatively small point serves the purpose best. This point may be slightly rounded, if desired.

In some situations, it may be advisable to use an agate bearing member; also, in some situations, it may be advisable to use a bearing member composed of, or comprising, a synthetic resin in a suitably hardened condition, as, for example, a phenolic condensation product in its final infusible and substantially insoluble state. The fibrous 125

material may be incorporated in such a resin, or fibrous material may be indurated by means of such a resin, if desired.

In the modification shown in Fig. 10, 9^a designates a fan-blade having its extremity provided with a lug 9^b which projects through a vertical slot in the upper end of the celluloid cylinder B^c. The fan may have several of its blades provided with 10 such lugs and the upper edge of the cylinder may have corresponding slots, or sockets, into which the lugs may pass when the fan is lowered into the cylinder. A close-fitting metal band 25 is forced onto the cylinder 15 above the lugs and thus the fan is securely fastened to the cylinder.

The foregoing detailed description has been given for clearness of understanding only, and no unnecessary limitations should 20 be understood therefrom, but the appended claims should be construed as broadly as permissible, in view of the prior art.

What I regard as new, and desire to secure by Letters Patent, is:

25 1. A stand for the purpose set forth, comprising more than two parallel metal disks provided with perforations, stiff resilient rods entered in said perforations and connecting said disks and held under flexure 30 thereby, and a central needle mounted on the upper disk.

2. A stand for the purpose set forth, com-

prising an upper disk, a lower disk, and two intermediate disks provided with rod-receiving perforations, stiff resilient rods entered in said perforations and connecting said disks, and lamps mounted on the intermediate disks.

3. A stand for the purpose set forth, comprising an upper disk, a lower disk, and two intermediate disks provided with rod-receiving perforations, stiff resilient rods entered in said perforations and connecting said disks, lamps mounted on the intermediate disks, and a thrust-bearing mounted centrally upon the upper disk.

4. A stand for the purpose set forth, comprising a suitable base, an upper disk and intermediate disks, lamps mounted on the intermediate disks, stiff resilient connecting members joining said disks near their peripheries and held under flexure by said disks, a needle socket mounted centrally on the upper disk, and a removable needle received by said socket.

5. A stand for the purpose set forth, comprising a suitable base, an upper disk and intermediate disks, lamps mounted on the intermediate disks, stiff resilient connecting members joining said disks near their peripheries, a needle socket mounted centrally on the upper disk, and a fibre needle received by said socket.

WOLFGANG HERMANN.
